DESIGN.

—o—
J. H. ALLEN.

KNOB.

No. 18,917.

Patented Feb. 12, 1889.

Attest,

Emma Arthur
George E. Cuse

Inventor:

John H. Allen

By Knight & Bro
J. H. A. B. S.

UNITED STATES PATENT OFFICE.

JOHN H. ALLEN, OF ST. LOUIS, MISSOURI, ASSIGNOR TO MEYER BROS. & CO.,
OF SAME PLACE.

DESIGN FOR A KNOB.

SPECIFICATION forming part of Design No. 18,917, dated February 12, 1889.

Application filed November 28, 1888. Serial No. 292,134. Term of patent 14 years.

To all whom it may concern:

Be it known that I, JOHN H. ALLEN, a citizen of the United States, residing at St. Louis, in the State of Missouri, have invented or produced a new and original Design for Knobs, 5 of which the following is a specification, reference being had to the accompanying drawing, forming part thereof.

The drawing is a perspective view showing my design applied to a knob having squared corners.

The leading feature of my design consists in a knob of approximately wedge shape hav-

ing an inclined or sloping surface on the outer face thereof, as shown in the drawing.

1 represents the outer portion of the knob, and 2 the shank or stem. The outer portion, 1, has an inclined or sloping surface on the outer face, 3.

What I claim is—

The design for a knob, substantially as herein shown and described.

JOHN H. ALLEN.

In presence of—

GEO. H. KNIGHT;

EDW. S. KNIGHT.
